ELECTROHYDRAULIC OPERATOR

Edwin E. Arnold, Pittsburgh, Pa., assignor to Westinghouse Electric & Manufacturing Company, East Pittsburgh, Pa., a corporation of Pennsylvania

Original application March 23, 1939, Serial No. 263,734. Divided and this application June 18, 1941, Serial No. 398,519

2 Claims.

(Cl. 103—84)

My invention relates to an electro-hydraulic operator, and more specifically to a specific type of hydraulic pump which is operated by the rotative effort of the shaft of an electric motor and which is useful, for example, to develop hydraulic pressure for effecting a linear thrust to operate a clutch, brake, door, or any other similar load device.

My present application is a division of my pending application Serial No. 263,734, filed March 23, 1939, entitled "Electro-hydraulic operators."

One object of my invention is to provide a viscosity screw-type pump which is capable of developing considerable pressure for a relatively small sized pump.

Another object of my invention is to provide a viscosity type of hydraulic pump which is simple, compact, rugged, and relatively small; yet which is capable of developing a high fluid pressure and, therefore, capable of employing a relatively small working piston area with consequent reduction in overall size.

A further object of my invention is to provide a reversely threaded viscosity type pump to avoid leakage at the seal formed with the pump casing.

Other objects and advantages will become more apparent from a study of the following specification, when considered in conjunction with the accompanying drawing, in which:

Figure 1 is a side view partly in cross-section, of a device embodying my invention;

Fig. 2 is a sectional view, taken along line II—II of Fig. 1; and

Fig. 3 is a partial view of a modification of a rotor embodying my invention.

Referring to Figure 1, numeral 1 denotes a casing which is partially filled with a fluid such as oil or the like. Fastened to the top of the casing is a cover member 2 upon which is mounted an electric motor 3, which drives a drive shaft 4. The drive shaft 4 has operatively connected thereto a substantially cylindrical solid boss member or rotor 5, which telescopically fits into a substantially cylindrical sleeve 6. This sleeve is insertable through an opening in the bottom of the casing and is removably secured to partition member 24 by a screw-threaded connection. Along the outer surface of the rotor 5 is a comparatively small and shallow, doubly wound or bifilar helical groove 7 which communicates with the upper or inlet chamber 31 and with an enlarged opening 8 in the rotor 5, which opens in registry with an opening 9 in the sleeve 6 which, in turn, is in communication with a pres-

sure or working chamber 10 situated at the bottom of said casing. Although the groove is described as being a double helix, it may likewise be a single helix, triple helix, or, in fact, any number of helices and of any desirable cross-section.

For example, referring to Fig. 3, a single helical groove 7' is shown. As shaft 4' rotates rotor 5' within sleeve 6', groove 7' picks up oil from the upper chamber 31 and because of the tendency of the oil to cling to the rotor due to its viscosity, it is propelled through the helical groove and it finally emerges from openings 8 and 9 into the pressure or working chamber wherein the oil develops a high fluid pressure. It will be noted that the oil is fed into the device shown in Fig. 3, by gravity. A greater pressure may be developed if the oil is fed under pressure, for example, as shown in Figs. 1 and 2.

Rotor 5 has on the top thereof a cylindrical portion 5a which is for the purpose of obstructing the passage of oil directly into the helical grooves. The oil is allowed to enter only through holes 5b in cylindrical portion 5a (see Fig. 2), thence the oil by centrifugal force is impelled radially outwardly along radial grooves 5c of rotor 5 emerging into the diametrically opposite starting points of the two helical grooves. Inasmuch as there is a great tendency for the oil, because of its pressure developed in opening 8, to leak along the surface of the lower rotor portion 5d and develop a pressure at the bottom of member 6, such portion 5d is provided with a helical groove which is wound opposite to groove 7, therefore, which will tend to move the oil upwardly and counterbalance this leakage tendency. To further counterbalance leakage, shaft 4 and rotor 5 are provided with a hole 4a which extends throughout their length and forms a bypass between the space at the bottom of rotor portion 5d and the upper chamber 31 through a radial hole 4b, which extends through shaft 4 thereby, in effect, equalizing the pressure at the bottom of rotor portion 5d with that in chamber 31, which chamber is at substantially atmospheric pressure. A collar 36 is screw-threaded to the lower part of a portion of shaft 4, the latter being of slightly reduced diameter and extending through rotor 5. The bottom of cylindrical sleeve 6 is closed by means of a screw-threaded plug 6a. A second substantially cylindrical sleeve is also removably secured to partition member 24 and projects through the lower part of the casing. Sleeve 11 telescopically surrounds a piston 12 having rings 13 and a thrust

rod extension 14 which projects out of the casing and terminates with any suitable connecting member 15, as shown, to which may be connected by means of linkages or levers, any load device such as a clutch, brake, door or any other similar device requiring a linear thrust for its operation. Supported on a boss or piston 12 is a sleeve member 16 having a collar 17 which is in engagement with a helical return spring 18. The other end of the return spring engages a bushing member 19 which is provided with a suitable fluid-tight gasket 20. Thus it will be seen that the return spring 18 normally urges piston 12 in the downward direction, which downward movement is arrested by a partially threaded stop member 21 which is screwed into the bottom portion of the casing and a buffer spring 22 which is rigidly connected to a boss 23 which is formed integral with piston 12, which spring is for the purpose of absorbing shock and forming a cushion or resilient stop for the piston as it completes its return or down stroke.

Partition member 24 which forms one of the walls of the pressure chamber 10, has a threaded hole therethrough into which is threaded a portion 25 of an electromagnetically operated by-pass valve 26. Valve 26 comprises a magnet coil 27 which is energized by wires 28 which are lead into the casing through a lead-in conductor 29, which is preferably connected with the motor circuit of motor 3 (not shown) so that the magnet will become energized at the same time motor 3 is energized and deenergized when the motor is deenergized. A by-pass port 30 is adapted to provide fluid communication between pressure chamber 10 and the upper chamber or intake chamber 31 when the magnet coil 27 is deenergized so as to permit the opening of the by-pass by a spring 32. When the magnet is energized, however, it attracts its armature and plunger 33 which is connected to the armature, thus effecting movement of the valve so as to close or at least restrict the by-pass port 30. The oil now goes up through passage 34 through holes 35 but can go no further due to the closure or seating of valve 33.

The operation of the device is as follows. When the motor 3 and magnet coil 27 are simultaneously energized, drive shaft 4 will rotate, thus rotating the rotor 5, the latter propelling fluid through its helical groove 7 from the intake chamber 31 along the sleeve member 6 to openings 8 and 9, finally into the pressure chamber 10, in which chamber a considerable pressure is produced by virtue of the high output characteristic inherent in a viscosity screw pump. The fluid pressure in chamber 10 acts on the working surface of piston 12 causing an upward movement of the piston against the restraining action of the return spring 18 and, in turn, causing an upward movement of thrust rod 14 which furnishes a power stroke for any suitable load device (not shown) such as a brake. During this time, the electromagnetically operated by-pass valve 26 is closed, hence the fluid is confined in the pressure chamber 10 and its laterally communicating passages. After the completion of the upward or power stroke of the thrust rod 14, motor 3 and coil 27 are deenergized, thus the rotation of member 5 is arrested and the by-pass valve 26 is opened by spring 32. Return spring 18 now forces the piston 12 downwardly, displacing fluid from the pressure chamber 10 upwardly through helical grooves 7 and finally into the upper or inlet chamber 31. An-

other path of fluid for the chamber 10 is through the port 30, which is now open, of the valve 26. The primary purpose of the by-pass valve 26 is to allow a larger fluid flow between the pressure chamber 10 and the inlet chamber 31 when the pump ceases to develop pressure in chamber 10, so as to allow a quick downward return of the piston. While the helical groove 7 in itself forms a by-pass between chambers 10 and 31, the groove is so small that the rate of flow of fluid therethrough would be comparatively small, thus requiring an appreciable length of time for the down stroke of the piston. It is within the scope of my invention to make electric motor 3 reversible so that after the upward movement or power stroke of the thrust rod 14, the motor may be plugged or reversed, thereby reversing the direction of rotation of the rotor 5, the effect of this reversal of rotation being to considerably increase the rate of flow of fluid from chambers 10 through groove 7 to chamber 31, thus considerably increasing the by-pass effect of the helical groove 7, thus decreasing the time required for the down stroke of the piston. The electromagnetically operated by-pass valve 26 may or may not be used simultaneously, depending on the time element desired for the completion of the return stroke or down stroke of the thrust rod 14.

The viscosity screw type of pump as described, is not as efficient as the propeller type of pump, such as shown and described in my copending application, Serial No. 257,940, filed February 23, 1939, entitled "Electro-hydraulic operators," and assigned to the Westinghouse Electric & Manufacturing Company, because of the large frictional losses inherently present in a viscosity screw type of pump. However, the pressure developed by the viscosity screw type pump as compared to the pressure developed by a similarly sized propeller, or even centrifugal type of pump, is enormously greater, partly due to the high rotational speeds obtainable by electric motors which thus impart a high velocity to the fluid in the screw or groove, particularly the layer of fluid immediately adjacent the surface of the groove formed in the rotor. Pressures above 1,000 pounds per square inch, for example, may be developed by a viscosity screw type pump as compared with pressures in the neighborhood of 15 pounds per square inch of a similarly sized ordinary propeller or centrifugal type of pump. It will thus be seen that an electro-hydraulic operator embodying the above screw pump is readily adapted in situations where space limitation is severe and where considerable force as applied by a thrust load is required, such as in large capacity brakes and the like. A wide and varied number of applications of the above-described device is obvious, such for example, as hoist clutches and brakes, machine presses, door operators, feeding machines, etc.

I am, of course, aware that others, particularly after having had the benefit of the teachings of my invention, may devise other forms of electro-hydraulic operators embodying my invention, and I, therefore, do not wish to be limited to the specific showings made in the drawing and the descriptive disclosure hereinbefore made, but wish to be limited only by the scope of the appended claims and such prior art that may be pertinent.

I claim as my invention:

1. A rotary viscosity pump comprising, in combination, a stationary cylindrical sleeve, a cylindrical body rotatably disposed within said sleeve

and a shallow groove on the surface of one of said cylindrical members, an oil supply, conduit means for feeding said oil supply substantially along the axis of said cylindrical rotary body and into said shallow groove for effecting centrifugal priming of said pump and ring means formed on said cylindrical rotary body closely fitted to said sleeve for confining oil in said groove so as to develop high pressure therein and to prevent ingress of oil thereto except through said conduit means.

2. A rotary viscosity pump comprising, in combination, a stationary cylindrical sleeve, a cylindrical body rotatably disposed within said sleeve,

5 an oil supply, a helically spiral shallow groove on the peripheral surface of said body for propelling oil longitudinally of said sleeve by viscosity action, an inlet groove formed in said cylindrical body for introducing oil first axially of said body and then radially thereof at one end so as to effect priming of said pump by centrifugal action when said body is rotated and ring means formed on said cylindrical rotary body closely fitted to said sleeve for confining oil in said groove so as to develop high pressure therein and to prevent ingress of oil thereto except through said conduit means.

EDWIN E. ARNOLD.
